CONVERSION OF HYDROCARBON OILS

Luis de Florez, Pomfret, Conn., assignor to The Texas Company, New York, N. Y., a corporation of Delaware

Application July 1, 1933, Serial No. 678,552

3 Claims. (Cl. 196—48)

My invention relates to the pyrolytic conversion of hydrocarbon oils to oils of lower boiling point such as gasoline, and has for an object the provision of a process for converting hydrocarbon oil, such for example as crude petroleum or reduced crude, gas oil or the like, to final products comprising gasoline, coke residue and, where desired, heavy fuel oil.

My invention has for further objects such improvements and operative advantages and results as may hereinafter be found to obtain.

My invention relates more particularly to a method of treating hydrocarbon oils wherein a charging oil is discharged into a distillation or dephlegmation zone receiving hot cracked vapors produced in the system. Dephlegmated vapors are withdrawn therefrom and fractionated to recover a gasoline distillate and a clean cycle stock. The cycle stock is heated to a relatively high cracking temperature in a heating zone as for example by passing through a heating coil in a suitable furnace. Cracked products from the heating zone, together with oil to be coked, which may comprise charging stock, or a mixture of residue and condensate from the dephlegmation zone, are discharged into a coking zone wherein liquid constituents are retained under coking conditions to reduce the same to a coke residue, and the vapors from the coking zone are led into the dephlegmation zone to constitute the supply of hot cracked vapors thereto.

A system of this character is of considerable advantage in that it makes possible a combined cracking and coking operation in which the advantages of clean circulation may be obtained. That is to say, the oil passed through the heating zone or cracking coil is of such a character as to enable it to be cracked under desirably high temperature and it may be in the vapor phase, and coking is accomplished largely by means of heat carried by the hot cracked products. In a system of this character, however, considerable excess heat may be available and it is to the better utilization of the excess heat and the consequent attainment of improved results that my invention is directed.

My invention contemplates, in a system of the general character recited hereinabove, by-passing a regulated portion of the hot cracked products from the heating zone around the coking zone and supplying them to the distillation or dephlegmation zone for the purpose of promoting cracking reactions therein, thereby improving the yield of light cracked distillate and effecting a

better balance of conditions throughout the system.

My invention further contemplates the selective treatment of separate charging stocks or separate portions of a suitable charging stock for the purpose of producing both coke and heavy fuel oil, as well as light cracked distillate.

In order that my invention may be clearly set forth and understood, I now prescribe, with reference to the drawing accompanying and forming a part of this specification, various preferred forms and manners in which my invention may be practiced and utilized. In this drawing,

The single figure is a more or less diagrammatic representation of a system for effecting the conversion of hydrocarbon oils according to my present invention.

Referring now to the drawing, a charging stock, such for example as a crude or reduced crude, a dirty gas oil or the like, is introduced from a source (not shown) through a conduit 1 by means of a pump 2 into a primary dephlegmator 3 which receives hot cracked vapors from elsewhere in the system through conduits 4 and 5.

Contact between the charging stock introduced through the conduit 1 and the hot cracked vapors introduced through the conduits 4 and 5 within the dephlegmator 3 results in a combined distilling and dephlegmating action, higher boiling constituents of the vapors being condensed and lower boiling constituents of the charging stock being volatilized. Moreover, due to the high temperature of the vapors entering the conduits 4 and 5 a certain amount of cracking takes place, resulting in the accumulation in the bottom of the dephlegmator 3 of a liquid comprising combined residual constituents of the charging stock and condensate from said vapors, which liquid is withdrawn from the bottom of the dephlegmator 3 through a conduit 6.

The vapors reaching the top of the dephlegmator 3 pass through a vapor line 7 to a fractionating tower 8, the interior of which may be provided with suitable plates or bubble trays 9 for the purpose of assisting in the fractionation.

By means of cool reflux oil introduced to the top of the fractionating tower 8 through a conduit 11, or by means of cooling effected in any other suitable manner, the vapors entering the fractionating tower 8 are subjected to partial condensation and fractionation for the recovery therefrom of higher boiling constituents comprising a clean cycle stock or gas oil which is withdrawn from the bottom of the fractionating tower 8 through a conduit 12. Uncondensed

vapors reaching the top of the fractionating tower 8 are removed therefrom through a vapor line 13 and passed to a condenser 14 wherein they are cooled to condense normally liquid constituents comprising light cracked distillate or gasoline. The mixture of condensate and uncondensed vapors passes through a line 15 to the gas separator 16 which is provided with a gas outlet 17 having a valve 18 and a condensate withdrawal line 19. The gasoline condensate may be entirely removed from the system through a branch conduit 20 having a valve 21, or a portion of this condensate may be withdrawn through a conduit 23 having a valve 24 and leading to a pump 25 which serves to return this portion of the condensate through the reflux conduit 11 to the fractionating tower 8.

The gas oil or cycle stock withdrawn from the fractionating tower 8, which is of such character that it may be subjected to drastic cracking conditions without difficulty, is, as aforesaid, withdrawn from the fractionating tower 8 through a conduit 12 wherein is located a valve 27 and is delivered by means of a pump 28 and a conduit 29 to a heating coil 31 located within a suitable furnace 32'. While in transit through the heating coil 31, the gas oil or cycle stock is heated to a cracking temperature under conditions favoring a high degree of cracking per pass. I may employ a temperature of from 850° to 1050° F. and a suitable superatmospheric pressure of, for example, from 150 to 750 pounds per square inch. The resultant highly heated cracked products then pass through a transfer line 32 having a valve 33 into a coking drum 34. A portion, however, of the hot cracked products from the coil 31 are withdrawn through the conduit 5 to be by-passed around the coking drum 34 for introduction directly into the dephlegmator 3. For this purpose the conduit 5 is provided with a valve 35 and communicates with the transfer line 32 at a point between the coil 31 and the valve 33. By manipulating the valves 33 and 35 the relative proportions of hot cracked products from the coil 31 delivered to the coking drum 34 and the dephlegmator 3, respectively, may be varied as desired.

Oil to be reduced to a coke residue is introduced into the coking drum 34 together with hot cracked products from the coil 31. Such oil may be delivered directly to the coking drum 34 through a conduit 36 having valve 37 or may be introduced into the transfer line 32 through a conduit 38 having a valve 39, and may variously comprise a portion or all of the liquid withdrawn from the bottom of the dephlegmator 3, a portion of the charging stock introduced through the conduit 1 or some other oil, suitable for coking.

When it is desired to introduce a portion or all of the liquid from the bottom of the dephlegmator 3 into the coking vessel 34 this oil may be returned through a conduit 41 having a valve 42 and a pump 43 and communicating with the conduit 6 between a valve 44 located therein and the dephlegmator 3, as well as with the conduits 36 and 38. By manipulation of the valves 42, 44, 37 and 39 any desired portion or all of the liquid withdrawn from the bottom of the dephlegmator 3 may be delivered either directly to the coking drum 34 through the conduits 6, 41 and 36 or to the transfer line 32 through the conduits 6, 41 and 38.

Alternatively, however, the valve 42 may be closed and all of the liquid withdrawn from the

bottom of the dephlegmator 3 may be removed from the system.

According to a modified form of my invention the oil supplied to the coking drum 34 for coking therein may comprise a second charging stock 5 which may differ in character from the charging stock introduced through the conduit 1 to the dephlegmator 3. In this instance, such a charging stock, for example, a reduced crude or a heavy residual oil resulting from a previous cracking 10 operation, may be withdrawn from a source (not shown) through a conduit 45 having a valve 46, to be delivered by means of a pump 47, the conduit 45, a conduit 48 having a valve 49 and the conduit 38, either to the transfer line 32 15 or to the conduit 36 for delivery to the coking drum 34.

In a still further modification of my invention, the stream of charging stock, delivered by the pump 2, through the conduit 1, may be divided 20 into two streams, one flowing to the dephlegmator 3 and the other direct to the coking drum 34. For this purpose I provide a branch conduit 51 having a valve 52 which communicates with the conduit 1 at a point between a valve 53 located 25 therein and the pump 2, and with the conduit 48.

The liquid constituents are retained within the coking drum 34 where they are maintained at a coking temperature, preferably in excess of 830° F., being thereby reduced to a coke residue which 30 may be removed from the coking drum 34 at the end of a run by means of the coke-boring apparatus provided for that purpose and indicated diagrammatically at 54. The evolved vapors are passed through the conduit 4 to the dephleg- 35 mator 3.

Pressures of, for example, 30 to 50 pounds per square inch, may be maintained in the coking drum 34, the dephlegmator 3 and the fractionating tower 8 although much higher pressures may 40 be employed, for example, 150 to 400 pounds per square inch. Where so desired, the vapors passing from the coke drum 34 to the dephlegmator 3, may be reduced in pressure by means of a valve 55 located within the conduit 4. The dephlegmator 3 and the fractionating tower 8 in the latter instance are maintained at a relatively reduced pressure, for example, 20 to 40 pounds per square inch or more, with respect to the pressure maintained within the coking drum 34. Prefer- 50 ably, however, the vapors are passed through the coking drum 34, the dephlegmator 3 and the fractionating tower 8 with a minimum reduction of pressure.

Suitable baffles 56 may be disposed within the 55 dephlegmator 3 for the purpose of promoting contact between the fresh charging stock and vapors therein and for the purpose of preventing residual or dirty constituents from passing through the conduit 7 into the fractionating 60 tower 8. Moreover, where desired, an additional light reflux oil may be supplied to the upper portion of the dephlegmator 3, the apparatus for this purpose being readily comprehended by those skilled in the art, and, therefore, not illus- 65 trated in the drawing.

By means of the regulated by-passing of hot cracked products from the coil 31 around the coking drum 34 and the introduction of these highly heated products into the dephlegmator 3, cracking reactions within the dephlegmator 3 are promoted, with the result that a high degree of conversion of the charging stock into desired liquid cracked distillate is made possible. At the same time any residual liquid returned from the de- 75

phlegmator 3 to the coking drum 34 is in such condition as to facilitate coking thereof. These results are accomplished by the utilization of excess heat in the hot cracked products leaving the coil 31 over and above that required for coking in the coking drum 34.

While I have hereinabove set forth and described various preferred procedures and conditions of operation by way of illustration of my invention, it will be understood by those skilled in the art that my invention is not limited to such illustrative examples but may variously be practiced and embodied within the scope of the claims hereinafter made.

15 I claim:

1. A combined cracking and coking process for converting hydrocarbon oil into products comprising a light distillate, heavy fuel oil and coke, which comprises subjecting a stream of oil while in transit through a heating coil to a cracking temperature, introducing a portion of said stream of cracked products from the heating coil into a coking chamber, directly admixing a residual oil to be coked from a source extraneous to the system with said portion of the stream being introduced into the coking chamber, retaining liquid constituents therein and maintaining them at a coking temperature to reduce them to a coke residue, passing evolved vapors from the coking chamber at a cracking temperature into a dephlegmating zone, introducing a stream of fresh charging stock into said dephlegmating zone and therein subjecting it to a cracking temperature by heat exchange with said vapors, introducing a further portion of the hot cracked products from said heating coil directly into said dephlegmating zone to promote the cracking of said fresh charging stock, withdrawing combined unvaporized charging stock and condensate from said dephlegmating zone and removing at least a portion of this combined material from the system as a heavy fuel oil product, removing vapors from said dephlegmating zone and introducing them into a fractionating zone wherein they are fractionated to produce a condensate heavier than gasoline, withdrawing condensate from the coking chamber at a cracking temperature into a dephlegmating zone, introducing a stream of fresh charging stock into said dephlegmating zone and therein subjecting it to a cracking temperature by heat exchange with said vapors, introducing a further portion of the hot cracked products directly from said heating coil into said dephlegmating zone to promote cracking of said portion of fresh charging stock introduced into said dephlegmating zone, withdrawing unvaporized fresh charging stock from said dephlegmating zone and removing from the system at least a portion of the unvaporized stock thus withdrawn, removing vapors from said dephlegmating zone and introducing them into a fractionating zone wherein they are fractionated to produce a condensate heavier than gasoline, withdrawing condensate from said fractionating zone and passing the same to said heating coil as charging stock therefor, removing vapors from said fractionating zone and condensing them to form the final light distillate.

2. A combined cracking and coking process for converting hydrocarbon oil into products comprising a light distillate, heavy fuel oil and coke, which comprises subjecting a stream of oil while in transit through a heating coil to a cracking temperature, introducing a portion of the hot cracked products into a coking chamber, introducing a heavy oil to be coked from a source extraneous to the system into said coking chamber, retaining liquid constituents therein and

maintaining them at a coking temperature to reduce them to a coke residue, passing evolved vapors from the coking chamber at a cracking temperature into a dephlegmating zone, introducing a stream of fresh charging stock into said dephlegmating zone and therein subjecting it to a cracking temperature by heat exchange with said vapors, introducing a further portion of the hot cracked products from said heating coil into said dephlegmating zone to promote the cracking of said fresh charging stock, withdrawing combined unvaporized charging stock and condensate from said dephlegmating zone and removing at least a portion of this combined material from the system as a heavy fuel oil product, removing vapors from said dephlegmating zone and introducing them into a fractionating zone wherein they are fractionated to produce a condensate heavier than gasoline, withdrawing condensate from said fractionating zone and passing the same to said heating coil as charging stock therefor, removing vapors from said fractionating zone and condensing them to form the final light distillate.

3. A combined cracking and coking process for converting hydrocarbon oil which comprises subjecting a stream of condensate oil while in transit through a heating coil to a cracking temperature, introducing a portion of the hot cracked products into a coking chamber, retaining liquid constituents therein and maintaining them at a coking temperature to reduce them to a coke residue, passing evolved vapors from the coking chamber at a cracking temperature into a dephlegmating zone, introducing a stream of fresh charging stock into said dephlegmating zone and therein subjecting it to a cracking temperature by heat exchange with said vapors, introducing a further portion of the hot cracked products directly from said heating coil into said dephlegmating zone to promote cracking of said portion of fresh charging stock introduced into said dephlegmating zone, withdrawing unvaporized fresh charging stock from said dephlegmating zone and removing from the system at least a portion of the unvaporized stock thus withdrawn, removing vapors from said dephlegmating zone and introducing them into a fractionating zone wherein they are fractionated to produce a condensate heavier than gasoline, withdrawing condensate from said fractionating zone and passing the same to said heating coil as charging stock therefor, removing vapors from said fractionating zone and condensing them to form the final light distillate.

LUIS DE FLOREZ. 60
